UNITED STATES PATENT OFFICE.

GEORGE E. BALL, OF TAUNTON, MASSACHUSETTS.

DESIGN FOR A PLATTER OR SIMILAR ARTICLE.

No. 39,511.

Specification for Design.

Patented Sept. 8, 1908.

Application filed June 11, 1908. Serial No. 437,988. Term of patent 14 years.

To all whom it may concern:

Be it known that I, GEORGE E. BALL, a citizen of the United States, residing at Taunton, in the county of Bristol and Commonwealth of Massachusetts, have invented a new, original, and ornamental Design for a Platter or Similar Article, of which the following is a specification, reference being had to the accompanying drawing, forming a part thereof.

Figure 1 is a plan view of a platter or similar article embodying my new design and Fig. 2 is a side elevation thereof.

I claim

The ornamental design for a platter or similar article as shown.

GEORGE E. BALL.

In presence of—

GEORGE E. CHAMBERS,
HERBERT O. WOOLLEY.
